UNITED STATES PATENT OFFICE

FRANCIS H. SCANTLEBURY, OF BROOKLYN, NEW YORK

BANK GRILLE CLOSURE

Application filed April 26, 1929, Serial No. 358,320. Renewed June 26, 1931.

This invention relates to direction closures for the grille windows used in banks for the various tellers, bookkeepers, etc., and for ticket windows at theatres and other places of amusement.

Closures of various kinds have been used to close the space at the bottom of bank window grilles to notify the customers that it is not to be used for the time being and usually having thereon some indication directing the customer to some other window of the bank. These devices merely rest on the ledge or shelf which forms the bottom of the window space and may be taken by anyone who felt 10 so disposed or may be accidentally pushed from the ledge.

The purpose of my invention is to provide a grille window closure which is provided with means to properly position it when slid 20 through the window opening by the bank teller or other official and is further provided with means which absolutely prevent withdrawal from the front of the window.

In the following detailed description I shall 25 refer to the accompanying drawings, where-in—

Figure 1 is a perspective view illustrating a portion of a bank partition with grilled windows and showing my closure in position 30 at one window.

Figure 2 is a vertical section taken perpendicularly through a portion of said partition and showing the lower part of the grille, a shelf or counter, with my device in use.

Figure 3 is a perspective view of my window closure from the rear; and

Figure 4 is a bottom view of one end thereof.

In the preferred form of my invention, the closure is a metal casting, made hollow for purposes of lightness. In cross section, as shown in Figure 2, it will be seen that the device is of general triangular formation having an inclined front face 10 and perpendicular end walls 11. The rear wall 12 is also perpendicular and may be interrupted along the upper edge throughout the central portion, sloping downwardly from either end to the top rear edge of the flat horizontal portion 13 which is adapted to slide closely under the

top rail or bar 23 of the window opening. The end walls have triangular brace extensions 14 forming continuations thereof which extend rearwardly from the bottom of the vertical wall 12, and are connected by a longitudinal web or foot member 15 having an up-standing flange 16, thus providing a groove or trough which may be engaged by the fingers to position the closure or withdraw it from the window. This trough forms a convenient 55 receptacle for holding pens and pencils. The end walls may be provided with laterally extending base flanges 17, although these are not essential. The bottom of these flanges are in the same horizontal plane with the lower 60 edge of the inclined front wall 10 and the under surface of the rearwardly projecting member 15.

In the front wall 10 there is provided a window 18 behind which is positioned a sign 70 19 bearing any desired inscription as, for instance, "Next window please". Obviously, any other inscription may be used that is found desirable. This sign may be held by a ribbed backing plate 20 secured to the front 75 wall 10 in any suitable manner as by screws 21 and nuts 22.

The manner of using the closure will be obvious from the illustrations and the function of the various parts of the structure will 80 be evident from the above description. The height of the top horizontal portion 10 is approximately equal to the depth of the window opening but so that it slides easily therein. The end wings of the vertical wall 12 which 85 project above the horizontal surface 10, provide stops which engage the rear face of the window bar 23, serving to properly position the closure in the window opening, preventing it from being pushed too far forward and 90 also preventing the closure from being pulled through the window from the front.

As will be observed in case the closure does not fit closely in the opening, it might be possible to tilt it sufficiently to withdraw it by 95 swinging the front edge upwardly if it were not for the member 15 projecting back of the vertical wall 12. Any effort, therefore, to tilt the device upwardly to remove the same 100 forwardly from this space will be prevented.

6 by reason of the fact that under these conditions the fulcrum point will be at the rear of the base portion 15 and in order to effect the tilting the flat top portion 13 which rests beneath the grille bar 23 would have to rise, this being prevented by the engagement of the grille bar therewith.

10 It will be evident that many changes can be made in the various parts of this closure device without departing from my invention and I wish to include all such modifications as are properly embraced within the scope of the claims.

I claim:

- 15 1. A closure for spaces below window grilles including a body adapted to fit within the space to be closed, stop portions projecting upwardly from the rear of the body to engage the window grille and limit forward movement of said closure, a base extension projecting from the body rearwardly of the stop portions to form a fulcrum to the rear of said stop portions when the body is tilted upwardly, and an upstanding flange at the 20 rear edge of the base extension and forming a groove extending longitudinally along the rear of the body to provide a finger grip for positioning the closure with respect to the grille.
- 25 30 2. A closure for the windows in bank grilles including a hollow body open at the bottom and having an inclined front wall, a pair of vertical end walls, a horizontal top wall extending rearwardly from the top of the front wall between said end walls and adapted to lie closely adjacent to the upper edge of the grille window, a vertical rear wall projecting above the top wall and joining said top wall at the rear thereof, a rear 35 base portion extending rearwardly from the bottom of the rear wall to thereby cause said top wall to engage the upper edge of the window when the body is tilted upon the rear edge as a fulcrum, thus preventing the withdrawal of the closure by a tilting movement.
- 40 45 50 55 60 65

In testimony whereof I affix my signature.
FRANCIS H. SCANTLEBURY.
